ATTORNEY

UNITED STATES PATENT OFFICE

JOHN F. GRACE, OF ARLINGTON, NEW JERSEY, ASSIGNOR TO WORTHINGTON PUMP AND MACHINERY CORPORATION, OF NEW YORK, N. Y., A CORPORATION OF VIRGINIA

SURFACE CONDENSER

Application filed December 12, 1928. Serial No. 325,626.

This invention relates to steam condensers and an object of the invention is to provide a condenser of the surface type having tubes therein arranged in a belt of substantially 5 uniform flow resistance throughout the length of the belt, the tube belt being arranged in folds providing steam spaces on the inlet sides of the folds and air spaces on the outlet sides of the folds, in which suitable 10 plates are positioned at predetermined points along the belt of tubes to provide the desired reduction of flow area in the direction of flow of steam through the condenser to obtain the proper velocity for scavenging in 15 proximity to the exit lanes in the condenser.

Another object of the invention is to provide a condenser as specified which embodies a primary air cooler therein for receiving the air from the air spaces and initially cooling 20 it, after which the air is passed to an air cooler exterior of the condenser for final cooling, thereby permitting maximum reduction of the temperature and consequently 25 of the volume of the air to facilitate its withdrawal from the condenser.

Another object of the invention is to provide means adjustable from the exterior of the condenser for regulating or controlling the air outlet of the primary air cooler.

With these objects in view, the invention consists in various features of construction and combination of parts, which will be first described in connection with the accompanying drawings, showing a condenser of the 30 preferred form embodying the invention, and the features forming the invention will be specifically pointed out in the claims.

Fig. 1 is a vertical cross section through the improved condenser.

Fig. 2 is an enlarged detailed section, and Fig. 3 is a view partly in side elevation and partly in longitudinal section of the improved condenser.

Referring more particularly to the drawings, the improved steam condenser of the surface type embodies a shell 1 which has its lower portions or half semi-cylindrical in shape while the sides of its upper section are of reduced radius with relation to the radius 45 of the semi-cylindrical lower section 1 as

clearly shown in Fig. 1 of the drawings, providing a condenser of less height than the conventional type of condenser which has the same capacity and tube area.

The shell 1 has the usual type of tubes 2 55 therein and these tubes are arranged in a belt of substantially uniform flow resistance throughout the length of the belt, and the belt is further arranged in folds, providing steam spaces 3 on the inlet sides of the folds 60 and air spaces 4 on the outlet sides of the folds. The air spaces 4 are partly lined with plates 5 to reduce the active length of the lanes to provide the desirable feature of reduction of flow area in the direction of flow 65 through the condenser to provide the proper velocity for thorough scavenging in proximity of the exit lanes of the condenser. The plates 5 make the area of steam exit from a tube bank smaller than the steam inlet area 70 to the said bank and consequently increase the velocity of outflow from the tube banks into the air spaces or exit lanes, thus improving the scavenging action of the condenser.

The lower portions of the inner folds of 75 the tube belt are divided off as shown at 6 by suitable plates 7 to provide a primary air cooler within the condenser and the air from the exit lanes 4 passes through the primary air cooler 6, out through an air outlet pipe 8 80 and into a final air cooler 9 which is positioned exterior of the condenser shell 1 and provides final cooling of the air to facilitate its handling and removal from the condenser.

While in the drawings a particular type of external air cooler is illustrated, it is to be understood that any approved type of air cooler may be employed without departing 85 from the spirit of this invention. The external air cooler 9 may be connected through the connection 10 with any suitable type of vacuum pump (not shown), for withdrawing the air from the condenser.

Means for adjusting the outlet of the primary internal air cooler 6 is provided which comprises a pair of plates 11 connected in any suitable manner by a connector 12 and placed along the inner air outlet sides of the sections 6 of the tube belt, which sections 95 100

form the air cooler, and in the passage way 13 which communicates with the air outlet pipe 8. The plates 11 have adjusting rods 14 connected thereto which are threaded through the shell 1 of the condenser and are 5 threaded through lock nuts 15 carried by the condenser shell 1 so that by rotation of the rods 14 the plates 11 may be moved towards or from the plate 7 for regulating the sizes of the outlet spaces 16 through which the air 10 passes from the cooling sections of the tubes 6 into the passage way 13. The rods 14 may have suitable hand wheels 17 thereon if it is desired, and while they are shown in the 15 drawings as rotatable, for adjusting the plates, it is to be understood that any other approved construction for moving the rods 14 and holding them in adjusted positions may be provided without departing from the 20 spirit of this invention.

It will be understood that the invention is not to be limited to the specific construction or arrangement of parts shown but that these may be modified widely within the invention defined by the claims.

What is claimed is:

1. In a steam condenser, a tube bank arranged in folds providing the steam spaces on the inlet sides of the folds and air spaces 30 on the exit sides of the folds, and plates along predetermined portions of the outlet sides of said folds for reducing flow area in the direction of flow of steam in the condenser.

2. In a steam condenser, a tube bank consisting of a belt of tubes of substantially uniform flow resistance throughout the length of the belt, and plates along predetermined parts of said belt for reducing flow area in 40 the direction of flow of steam in the condenser.

3. In a steam condenser, a tube bank consisting of a belt of tubes of substantially uniform flow resistance throughout the length 45 of the belt, said belt being arranged in folds providing steam spaces on the inlet sides of the folds and air spaces on the exit sides of the folds, an air cooling space for receiving air from said air spaces, and adjustable 50 means for regulating the outlet of said air cooling space.

4. In a steam condenser, a tube bank arranged in folds providing steam spaces on the inlet sides of the folds and air spaces on 55 the exit sides of the folds, plates along predetermined portions of the outlet sides of said folds for reducing flow area in the direction of flow of steam in the condenser, an air cooling space for receiving air from said air 60 spaces, and adjustable means for regulating the outlet of said air cooling space.

5. In combination, a steam condenser including a shell, a primary air cooler within 65 said shell, and a final air cooler exterior of said shell and receiving air from said pri-

mary air cooler, and means for regulating the outlet of said primary air cooler.

6. In combination, a steam condenser including a shell, a primary air cooler within 70 said shell, and a final air cooler exterior of said shell and receiving air from said primary air cooler, and adjustable means adjustable from the exterior of said shell for regulating the outlet of said primary air cooler.

7. In a steam condenser, a tube bank consisting of a belt of tubes of substantially uniform flow resistance throughout the length of the belt, plates along predetermined parts of said belt for reducing the flow 80 area in the direction of flow of steam in the condenser, an air cooling space within said condenser, and adjustable means for regulating the outlet of said air cooling space.

8. In combination, a steam condenser 85 including a shell, a tube bank within said shell arranged in folds providing steam spaces on the inlet sides of the folds and air spaces on the exit sides of the folds, a primary air cooler within said shell, for receiving air from 90 said air spaces and a final air cooler exterior of said shell and receiving air from said primary internal air cooler, and plates along predetermined portions of the inlet sides of 95 said folds for reducing flow area in the direction of flow of steam in the condenser.

9. In a condenser, a tube bank having a portion thereof divided off to provide an air cooler, and adjustable means for controlling the air outlet of said cooler.

10. In a condenser, a tube bank having a portion thereof divided off to provide an air cooler, a plate moveable along the outlet side of said air cooler, and adjustable means for moving said plate to control the air outlet of 105 said air cooler.

11. In a condenser, a tube bank having a portion thereof divided off to provide an air cooler with an air outlet space therein, plates within said space, and means adjustable from 110 the exterior of the condenser for moving said plates to regulate the air outlet of said air cooler into said space.

12. In a steam condenser, a shell having its lower part semicircular in shape and its upper part with sides curved on a radius less than the radius of the lower part, a tube bank within said shell and arranged in folds providing steam spaces on the inlet sides of the folds and air spaces on the exit sides of the 120 folds, and plates along predetermined portions of the outlet sides of the folds for reducing flow area in the direction of flow of steam in the condenser.

13. In a steam condenser, a shell having its lower part semicircular in shape and its upper part with sides curved on a radius less than the radius of the lower part, a tube bank within said shell and arranged in folds providing steam spaces on the inlet sides of the 125 130

5 folds and air spaces on the exit sides of the folds, and plates along predetermined portions of the outlet sides of the folds for reducing flow area in the direction of flow of steam in the condenser, an air cooling space within said shell for receiving air from said air spaces, and adjustable means for regulating the outlet of said air cooling space.

14. In a steam condenser, a shell having 10 its lower part semicircular in shape and its upper part with sides curved on a radius less than the radius of the lower part, a tube bank within said shell and arranged in folds providing steam spaces on the inlet sides of the 15 folds and air spaces on the exit sides of the folds, and plates along predetermined portions of the outlet sides of the folds for reducing flow area in the direction of flow of steam in the condenser, a primary air cooler 20 within said shell for receiving air from said air spaces, and a final air cooler exterior of the said shell and receiving air from said primary air cooler.

15. In a steam condenser, a shell having its 25 lower part semicircular in shape and its upper part with sides curved on a radius less than the radius of the lower part, a tube bank within said shell and arranged in folds providing steam spaces on 30 the inlet sides of the folds and air spaces on the exit sides of the folds, and plates along predetermined portions of the outlet sides of the folds for reducing flow area in the direction of flow of steam in the condenser, a primary air cooler 35 within said shell for receiving air from said air spaces, and a final air cooler exterior of the said shell and receiving air from said primary air cooler, and means for regulating the outlet of said primary air 40 cooler.

In testimony whereof I affix my signature.
JOHN F. GRACE.
